UNITED STATES PATENT OFFICE

OTTO BUTZBACH, OF CHICAGO, ILLINOIS

LAUNDRY APPARATUS

Application filed December 31, 1928. Serial No. 329,462.

My invention relates to a laundry apparatus. It will be described with particular reference to a machine for drying clothes.

In drying clothes by the circulation of heated air therethrough, the clothes are usually confined rather compactly in a relatively small container in order to economize in the amount of heated air required to be circulated through the container. As soon as the heated air passing through the clothes becomes saturated with moisture it must be expelled since thereafter it will no longer effect a drying action.

One of the chief difficulties encountered in drying clothes is to insure that all of the air passing through the container will come in contact with the clothes and become saturated with moisture before being expelled from the container. When only a portion of the air is efficiently utilized there is a waste of heat in the unsaturated air which is expelled and also a waste of power in conveying the larger amount of heated air required to remove the moisture from the clothes.

The problem involved is therefore to obtain such a distribution of the air that the materials to be dried will be as uniformly exposed thereto as practical considerations will permit. Apparatus has been devised heretofore which has attempted to obtain a proper distribution of the air by blowing the air through a plurality of vents into the clothes. However, experience has shown that heretofore this method proved unsatisfactory on account of the accumulation of lint in certain parts of the drying apparatus tending to impede the circulation of air.

A further disadvantage in the use of laundry machines heretofore used is found in the amount of labor and hazard involved in removing the clothes from the machine.

An object of my invention is to provide an improved laundry machine.

A further object is to provide a drying apparatus having a simple and effective means for circulating air through the clothes.

A further object is to provide a drying apparatus which economically and efficiently utilizes the air to produce a comparatively

large drying action.

A further object is to provide a drying apparatus in which heated air is blown through the apparatus to dry the clothes and when the clothes are dry, a simple adjustment causes air of atmospheric temperature to be drawn through the clothes to cool them.

A further object is to provide an improved laundry machine from which the clothes may be conveniently removed without the necessity of the operator reaching into the machine.

A further object is to provide a laundry machine which may be stopped in such a position that when the doors are opened the clothes will drop by their own weight from the machine.

A further object is to provide a laundry machine having two positions of the clothes container, in one of which the clothes are loaded into the container, and in the other it may be unloaded.

A further object is to provide a laundry machine having an improved locking device for locking the door of the container.

Other objects and advantages will appear from the detailed description of the apparatus.

In accordance with the general features of the invention, a revoluble foraminated cylindrical container is mounted in the casing and air is admitted axially to two drums at the ends of the container communicating with an eccentrically mounted distributor extending longitudinally from drum to drum. The air passes from the distributor through the clothes in the drum and out of the foraminations in the cylinder. It has been found that this apparatus reduces the volume of air ordinarily required substantially one-half. The cylinder and casing are each provided with doors, the door in the casing being large enough and located near the bottom in such a position that the door of the cylinder may be in position for loading clothes into the machine and retain them therein and in another position for unloading the clothes and allowing them to drop by gravity from the machine.

In the drawings,

Fig. 1 is a front elevation partly in section of the apparatus of my invention;

Fig. 2 is a vertical sectional view taken on the lines 2—2 of Fig. 1, arrows indicating the flow of hot drying air;

Fig. 3 is a plan sectional view of the apparatus taken on the line 3—3 of Fig. 2;

Fig. 4 is a back elevation with parts broken away showing the interior of the apparatus;

Fig. 5 is a horizontal sectional view taken on the line 5—5 of Fig. 2;

Fig. 6 is a cross section taken generally on the line 6—6 of Fig. 5;

Fig. 7 is a sectional view taken on the lines 7—7 of Fig. 4; and

Fig. 8 is a diagrammatic view similar to Fig. 2, arrows indicating the flow of cooling air.

The apparatus comprises in general a substantially rectangular housing 11 for the fan, heating coils, and conduits of the apparatus, and a casing 12 having a revoluble cylinder 13 therein and supported upon housing 11 and overhanging the housing in such a position that the axis of the cylinder is substantially in vertical alignment with one side of the housing.

The cylinder has a foraminated portion 15 and an imperforate portion 16. At the ends 20 of the cylinder are spaced partitions 17 and 18 which form air drums at the ends of the cylinder. The portions of partitions 17, extending along the imperforate portion of the cylinder are cut away and a partition 19 extending from drum to drum is supported by partitions 17 and the cylinder forming an eccentric channel in communication with the air drums and extending the length of the cylinder.

The end partitions 18 are provided with concentric rings 22 surrounding axial openings into the drums. A longitudinal chamber 23 extends the full length of the casing and is connected at each end to the air drums at the ends of the cylinder by a channel 24. Thus air under pressure in chamber 23 will pass through channels 24 into the air drums at the ends of the cylinder and into the longitudinal channel passing through the perforations in partition 19 into the container, and through the clothes, leaving the cylinder through the foraminated portion 15. The casing is spaced from the cylinder a distance to provide a suitable annular air space around the cylinder from which the air passes into a somewhat funnel shaped chamber 25 which is connected to the casing throughout the length of the casing.

Air chamber 25 tapers at its lower end and leads into a space 26 formed between walls 27 and 28. The space 26 may be connected either to a stack 31 leading to the atmosphere, or to an intake chamber 32 for fan 37, depending upon the position of damper 33. When

the damper is in its upper position, as shown in Fig. 2, space 26 is in communication with the stack, and when the damper 33 is dropped to its lower position space 26 is in communication with intake chamber 32. Intake chamber 32 has at its forward side a circular aperture 34 which may be closed by a damper 35. At the opposite end, intake chamber 32 connects through a tube 36 to the intake of fan 37.

Located in the forward part of the housing 75 is a heating chamber 38 provided with a plurality of heating coils or other suitable heating elements. When damper 35 is open and damper 33 is in its upper position, the fan will draw atmospheric air through the heating coils in housing 38 into intake chamber 32, expelling air upwardly into a channel 41. Connected to air chamber 23 is an auxiliary air chamber 43 provided with openings 44 and 45. The opening 44 is controlled by a damper 46 and the opening 45 is controlled by a damper 47. Dampers 46 and 47 are secured to a shaft 48 which tends to move them in unison in such a manner that when damper 46 is closed, damper 47 is open and vice versa. 90

Air expelled by the fan 37 will be prevented from entering the stack 31 when damper 47 is open and will be directed into the auxiliary air chamber 43 and thence to air chamber 23 through the cylinder and casing, as described above, and out of the air chamber 25 into the space 26, damper 33 being in its upper position at this time, the air will pass from space 26 into the stack and out of the apparatus. 100

Damper 33 is mounted on a shaft 51 to which a lever 52 is rigidly secured. Damper 35 is pivoted on a shaft 53 to which lever 54 is rigidly attached. Levers 52 and 54 are interconnected by a link 55. Extending upwardly from lever 52 is a link 56, the upper end of which is connected to a lever 57 mounted on a shaft 61. Shaft 61 carries a lever 60 connected to a lever arm 58 rigidly secured on shaft 48 through a link 59, thus interconnecting all of the dampers. Shaft 61 extends longitudinally at the back of the machine to one end and is connected by a lever 62 secured thereon and a suitable link 63 to an operating handle 64 located in convenient 110 reach of the operator. 115

In order to dry the clothes placed in the cylinder, handle 64 is actuated to raise damper 33, lower damper 35, close damper 46, and open damper 47. The fan will then blow 120 air through the cylinder and casing as described and discharge the moisture saturated air from the stack.

After sufficient heated air has been circulated through the system to dry the clothes 125 in the cylindrical container, it is desirable to circulate air through the clothes at atmospheric temperature in order to cool the clothes before removing them from the apparatus. As shown in Fig. 8 the apparatus has 130

been adjusted to circulate cool air through the clothes. Operating handle 64 has been actuated to change the position of all of the dampers, raising damper 35 to a position covering aperture 34 of intake chamber 32, thus disconnecting the intake chamber from communication with the housing for the heating coils. At the same time damper 33 has been dropped to connect air chamber 32 with the air chamber 35, causing the fan to draw the air from chamber 35.

Actuation of the operating handle has also served to close damper 47, thus connecting the discharge end of the fan to the stack and opening damper 46 so that the auxiliary air chamber 43 will be in communication with the atmosphere, permitting the fan to draw atmospheric air into the opening 44 through the cylinder and casing and expel it through the stack. During the blowing of the heated air through the apparatus, there is a tendency for lint to accumulate in the apparatus which tends to disturb the passage of air. However, the suction of the fan during the cooling process removes all of the accumulated lint and discharges it from the stack of the apparatus.

Casing 12 is provided with a door 71 which may comprise substantially one-fourth of the peripheral length of the cylinder. Door 71 is slidably mounted in grooves 72 located at the ends of the casing and the lower portion of the casing is provided with a groove 73 into which the lower edge of the door rests when the door is closed. In order to provide a convenient apparatus for opening the door, a motor 74 is mounted at one end upon the casing. The door is provided at each end with gear sectors 75 meshing with gears 76 which are rotated by gears 77 mounted upon a shaft 78. The gears 76 are carried by arms 81 pivotally mounted upon a shaft 78. When the motor is energized it will rotate shaft 78 and gears 77 and also gears 76, causing the door to be raised. When the door has been raised to a certain position, cams 82 located at the ends of gear sectors 75 will strike arm 81 tending to disengage gears 76 from gear sectors 75 by pivoting arms 81 about their pivot. The end of arms 81 are provided with springs 83 adapted to engage notches in detents 84 so that when the gears 76 are disengaged from gear sectors 75 arms 81 will tend to maintain the gears out of engagement.

The door may be lowered by the hand, for which purpose suitable grips 88 are provided on the door. The upper end of gear sectors 75 are provided with suitable cam surfaces 80 which engage arms 81 when the door reaches its lowermost position, tending to reengage gears 76 with the gear sectors 75, the motor having been stopped in the meantime.

The cylinder may be divided into one, two, or more compartments by a partition 91, and

each compartment is provided with a door 92 adapted to slide in suitable grooves 93, and a groove 94 is provided at the lower side of the openings into the cylinder to provide a suitable support for the lower edge of the door when the door is closed. The interior of the cylinder is provided with a plurality of ribs 95 which assist in tumbling the clothes within the cylinder when the cylinder is rotated. These ribs extend longitudinally the full length of the cylinder. The base of one of the ribs 95 is open and is provided at one side with a longitudinal flange 96 and the upper end of each of the doors is provided with a hook portion 97 adapted to overlap flange 96 when the doors are closed, thus providing a complete support for the entire periphery of each of the doors when in their closed position. Doors 92 are provided with suitable handles 98 by which the doors may be opened.

In order to secure the doors of the cylinder against opening while the apparatus is in operation, a plurality of blocks 101 are mounted in the hollow space of rib 95. Each of these blocks has a latch 102 pivotally mounted thereon and adapted to extend over the hooks 97 to lock the doors in their closed position. The latches are all interconnected by a bar 103. On one of the blocks 102 a lever 104 provided with a handle 105 is pivotally mounted. Lever 104 has a groove 106 therein into which a pin 107 of the adjacent latch 102 extends.

By rotating lever 104 to the dotted line position as shown in Fig. 5, latches 102 will be rotated to such a position as to free the hooks 97 and allow the doors to be opened.

It will be seen that when the latches are in this position the lever will be within the periphery of the cylinder so that the door may be moved upwardly by the rib.

In loading clothes or other materials to be dried into the apparatus door 71 of casing is first opened and then the doors to the cylinder are opened. The cylinder is then moved to such a position that the upper edge of its opening will be in alignment with the upper edge of the casing door, so that the cylinder will be in a position in which clothes may be conveniently placed into the cylinder. The doors are then closed and the cylinder doors are locked in their closed positions. The clothes are then dried, as described above, the cylinder being in the meantime oscillating to and fro approximately 7 or 8 revolutions in one direction and then 7 or 8 revolutions in the opposite direction to prevent tangling and tearing of the clothes. After the clothes have been dried, the door to the casing is opened and the doors to the cylinder are opened. The cylinder may then be moved to such a position that the lower edge of the opening into the cylinder is in alignment with the lower edge of the casing door. In this position of the cylinder the

clothes will fall by gravity from the cylinder into any suitable receptacle, such as a truck 107. This construction obviates the necessity of the operator reaching into the apparatus in order to remove the clothes from the container.

In order to permit air to be drawn through the cylinder and casing at all times, even when the heated air is circulated through the

10 clothes, an opening 111 and a damper 112 therefor are provided in the lower wall of air chamber 23. Damper 46 is then rotated upon shaft 48 by unscrewing a set screw 113 so that damper 46 may remain closed while

15 damper 33 is in its lower position, damper 35 in its upper position and damper 47 is closed. The air then is drawn through the cylinder and casing through intake chamber 35 and into the fan and expelled from the

20 fan into the stack. Drawing the air out of the casing and cylinder creates a low pressure in the air chamber 23, and since this is closed except for opening 111, air will be drawn over the heating coils into chamber 23.

25 Having thus described the nature and embodiments of my invention, what I desire to secure by United States Letters Patent is as follows:

1. In a drying apparatus, a fan, an exhaust 30 stack, a cylinder, a casing enclosing the cylinder, means operable to cause said fan to discharge either into the stack or into the cylinder, an intake chamber for the fan, a heating chamber, and means for connecting said intake chamber either to the heating chamber or to the casing to withdraw air therefrom.

2. In a drying apparatus, a hollow perforated cylinder, a perforated channel eccentrically located in the cylinder and extending longitudinally thereof, the perforations in said channel being adapted to direct air inwardly from the periphery of the cylinder, a drum having an axial opening positioned 45 at the end of the cylinder and communicating with the channel, a fan, an exhaust stack, means operable to cause the fan to discharge either into the exhaust stack or into the axial opening in the cylinder drum, a casing enclosing the cylinder, an outlet chamber communicating with the casing, an intake chamber for the fan, a heating chamber; and means 50 operable to connect the intake chamber of the fan with the heating chamber or with the outlet chamber of the casing.

3. In a drying apparatus, a hollow perforated cylinder, a perforated channel eccentrically located in the cylinder and extending longitudinally thereof, the perforations in said channel being adapted to direct air inwardly from the periphery of the cylinder, a drum having an axial opening positioned 60 at the end of the cylinder and communicating with the channel, a fan, an exhaust stack, means operable to cause the fan to discharge

either into the exhaust stack or into the axial opening in the cylinder drum, a casing enclosing the cylinder, an outlet chamber communicating with the casing, an intake chamber for the fan, a heating chamber, and means 70 connecting the intake chamber of the fan to the heating chamber when the fan is discharging into axial opening of the cylinder and to the outlet chamber of the casing when the fan is discharging into the stack.

4. In an apparatus for laundering clothes, a support, a casing mounted upon the support at a sufficient height to allow a truck to be moved under the casing from the front of the machine and overhanging the support, said casing having an opening in the overhanging portion of the casing, and a cylinder revoluble in the casing and having an opening therein, said openings being provided with closures, the opening in the cylinder being adapted to be moved to a position relative to the opening in the casing to permit clothes to fall out of said openings by gravity when the closures are open.

5. In a laundering apparatus, a cylinder having an opening therein, a hollow rib extending into the cylinder and located along an edge of the opening, a plurality of grooves along the sides of the opening, a door slidably mounted in said grooves and adapted to move over said rib when being opened, a latch in said rib, and means for operating said latch to lock the door in its closed position.

6. In a laundering apparatus, a cylinder having an opening therein, a plurality of grooves on three sides of said opening, a hollow rib extending into the cylinder on the remaining side of the opening, a door slidable in the grooves, a flange in the rib, a hook-shaped edge on the door adapted to engage said flange when the door is closed, a plurality of latches for retaining said hooked portion in engagement with the flange to lock the door, and means operable to disengage 100 the latches to unlock the door.

7. In a laundering apparatus, a cylinder having an opening therein, a hollow rib extending into the cylinder and located along an edge of the opening, a door for said opening, a plurality of latches movably mounted in said rib for locking the door, a bar interconnecting the latches, and means for moving the bar to operate the latches.

8. In a laundering apparatus, a cylinder having an opening therein, a hollow rib along an edge of the opening, a door for the opening, a plurality of latches for locking the door, a bar for interconnecting the latches to lock and unlock the door, and a lever for operating the bar, said lever being within the rib when the door is locked or unlocked.

9. A laundry dryer comprising a casing having an off-set cylindrical portion with an opening therein, a closure for said opening,

70

a rotary clothes container having an opening mounted within said off-set portion, a closure for said opening, the opening in said off-set portion arranged to permit clothes in the clothes container to drop by gravity through both openings when said openings are aligned.

10. A laundry dryer comprising a casing having an off-set cylindrical portion, and a cylinder having a side opening therein rotatably carried within said cylindrical portion, the cylinder over-hanging the casing along the off-set side thereof, said casing having an opening in the off-set portion, both of said openings being provided with closures, the opening in the cylinder being adapted to be moved to a position relative to the opening in the casing to permit clothes to fall outside of the casing by gravity when the closures are opened.

20 11. In an apparatus for laundering clothes, an off-set support, a casing mounted upon the support and over-hanging on one side, said casing having an opening in the over-hanging portion, a closure for said opening, said opening being so arranged to be above a movable clothes container stationed in front of the machine, and a cylinder revoluble in said casing and having a clothes opening therein, said cylinder revoluble so that the opening 30 therein registers with the opening in the casing to allow clothes to fall through said openings into the movable container.

In witness whereof, I hereunto subscribe my name this 11th day of December, 1928.

OTTO BUTZBACH.
